Primary Examiner — Samantha Q Lawrence*Assistant Examiner* — Melissa Adriane Santos(74) Attorney, Agent, or Firm — Foley & Lardner LLP(57) CLAIM

We claim the ornamental design for a light fixture, as shown and described.

DESCRIPTION

FIG. 1 is a perspective view of a light fixture;
FIG. 2 is a front view of the claimed design shown in FIG. 1;

FIG. 3 is a rear view of the claimed design shown in FIG. 1;

FIG. 4 is a side view of the claimed design shown in FIG. 1;

FIG. 5 is another side view of the claimed design shown in FIG. 1;

FIG. 6 is a top view of the claimed design shown in FIG. 1; and,

FIG. 7 is a bottom view of the claimed design shown in FIG. 1.

The broken lines shown in FIGS. 1-7 illustrate portions of the light fixture that form no part of the claimed design.

1 Claim, 6 Drawing Sheets(56)
